TYPEWRITING MACHINE

William F. Helmond, West Hartford, Conn., assignor to Underwood Elliott Fisher Company, New York, N. Y., a corporation of Delaware

Application February 25, 1937, Serial No. 127,609

8 Claims. (Cl. 197—102)

This invention relates to molded and other solid keys for typewriting machines. The key is made in one piece of Bakelite, Phenolite, Celluloid, or other suitable material, and preferably is dished. For certain purposes the key may be molded of soft rubber or other suitable cushioning material.

An aim of the invention is to dispense with the usual key cup, and also to simplify the construction and reduce the cost of manufacturing and assembling, and a further aim is to provide for ready attachment and detachment of the key.

The key-stem is a forked resilient member. It may be either a part of the lever, or a separate piece fastened by rivets, welding, or otherwise to the end of the key-lever.

The forked ends of the stems may be drawn together to allow easy removal or attachment of the key.

20 The upper ends of the key-stems are formed in two arcs of 90°, which curve outwardly. In plan these ends appear square or rectangular, with two sides contractible inwardly or towards the center.

The key can be easily attached or removed from 25 the stem, and also will not turn on the stem or loosen from it. This advantage is gained by constructing the key or key-head with a squared bottom opening, with two of the sides of the opening undercut and forming a seat into which fit the curved ends of the key-stem. The other opposite sides are correctly spaced for fitting tightly against the flat sides of the key-stem.

A further feature of the invention is to provide 35 a metal insert to be imbedded or inserted into the key-head. This insert retains the features above described for the opening in the bottom of the key-head, and will prevent chipping or damage to the type-head when it is being removed or attached. Furthermore this insert will permit the use of resilient cushioning material, such as rubber, for the key-head.

The rubber key may have a hollow space or air chamber, to increase the key resilience.

40 The cost of making and assembling the key is reduced and the operator is enabled to choose keys that are most suited to his individual needs, at a relatively lower cost.

Other features and advantages will hereinafter 45 appear.

In the accompanying drawing,

Figure 1 is a view of the end of the type-key stem, with the type-key head in place, and in section.

50 Figure 2 corresponds to Figure 1 and shows the

type-key stem contracted and the type-key head partially removed.

Figure 3 is a side view of Figure 1.

Figure 4 is an isometric view of the type-key stem attached to the end of the key-lever.

5 Figure 5 shows the type-key stem as part of the key-lever.

Figure 6 is an isometric drawing of the type-key stem and type-key head, with parts broken away to show the construction.

10 Figure 7 is an isometric drawing of the metal insert for the type-key head.

Figure 8 is a section of a type-key head made of Bakelite or similar material without a metal insert.

15 Figure 9 is a sectioned drawing of a Bakelite type-key head with a metal insert.

Figure 10 is a sectioned drawing of a type-key head made of resilient material such as rubber.

20 Figure 11 is a sectioned drawing of a resilient type-key head having an air chamber.

Figure 12 is a view of the bottom of Figure 8.

Figure 13 is a view of the bottom of Figure 9.

25 Figure 14 shows a bank of typewriter keys with a pair of pliers in position to remove the key head.

The type-key stem 20 has two vertical sides 21 and 22 having on their upper ends two curved portions 23 and 24, which are curved through arcs of 90° as shown in Figure 1. The curved portions 23 and 24 have rounded ends 25 and 26 for fitting into corresponding rounded surfaces 27 and 28 of the curved sides 29 and 30 of the metal insert 31 which is imbedded in the key-stem head 32. The insert 31 has two flat sides 33 and 34 which fit against the flat sides or ends 35 of 21 and 22, as shown in Figure 3.

The two vertical sides 21 and 22 are resiliently held together, at the lower portion of the key-stem 20, by a back portion 36 of the key-stem 20. 40 As shown in Figure 4, the key stem 20 may be fitted over the end of the key-lever 37, where it is securely fastened with rivets 38. An alternative means is shown in Figure 5, where the key-stem 20 and the key-lever 37 are made of one piece. 45

If the key-stem head 32 is made of Bakelite or similar material it may be desirable not to use the insert 31. In such a case the key-stem head 32 may be made, as shown in Figure 8, with the rectangular opening 39 in the bottom of the key-head 32. Two sides 40 and 41 of the opening 39 are undercut to fit the rounded ends 25 and 26 of the sides 21 and 22. The other sides 43 are flat to fit snugly against the flat sides 35 of the key-stem sides 21 and 22.

If the key-stem head 32 is of resilient material such as rubber, the head 32 may be molded around the insert 31, or the head 32 may be molded and the insert 31 inserted afterwards. In either case, the edges 44 may be formed to help hold the insert 31 in place. To get added resiliency the rubber key-stem head 32 may be molded with an air pocket 45, as shown in Figure 11.

The following is a description of how the key-stem head 32 may be rigidly fixed to the key-stem 20. Normally the backing 36 holds the sides 21 and 22 resiliently apart and to attach the key-stem button 32, it is first necessary to squeeze the sides 21 and 22 together with a pair of pliers 47 or some other suitable means. When sides 21 and 22 are drawn together the type-stem head 32 will fit on as the ends 25 and 26 will clear the sides 29 and 30, and the sides 33 and 34 of insert 31 will position the head 32. When the key-stem 20 sides 21 and 22 are released and allowed to return to their normal position the rounded ends 25 and 26 will fit into the sides 29 and 30, thereby preventing the head 32 from coming loose. If the Bakelite head 32 is used without an insert, the procedure remains the same and the rounded ends 25 and 26 will fit into the undercut sides 40 and 41. As the faces 25 and 26 and 35 of the key-stem 20 are at right angles with each other and fit sides 28 and 29 and 33 and 34 of the key-stem head 32, which are at right angles with each other, it is impossible for the key-stem head 32 to turn on the key-stem 20.

Variations may be resorted to within the scope of the invention, and portions of the improvements may be used without others.

Having thus described my invention, I claim:

1. The combination with a metal type-key stem having co-extensive resilient members, corresponding end portions of which are directed outwardly at right angles from the members, of a type-key head including a metal plate secured thereto, said plate having opposed marginal portions inturned to closely fit over the end portions of said members, to securely hold said type-key head releasably on said stem.

2. The combination with a metal type-key stem having co-extensive resilient members, corresponding end portions of which are directed outwardly at right angles from the members, of a type-key head including a rectangular metal plate affixed thereto, said metal plate having opposed margins inturned to substantially embrace the free ends of said stem-members, the adjoining margins of said plate depending abruptly therefrom to engage the edges of said stem-members, to securely hold said type-key head releasably on said stem.

3. The combination with a metal type-key stem having co-extensive resilient members corresponding end portions of which are directed outwardly at right angles from the members, of a type-key head formed of moldable material and having a constricted recess therein, of a metallic member embedded in said type-key head to re-

inforce same and having groove-defining portions closely fitting over the end portions of said members and merging into the constricted region of the recess to facilitate removal of the type-key head from said stem.

4. The combination with a metal type-key stem having co-extensive resilient members corresponding end portions of which turn outwardly at substantial angles from the members, of a resilient type-key head formed of yieldable material and including a substantially flat metal plate embedded therein, opposed margins of said plate being inturned to closely fit over the end portions of said stem members for securely holding said type-key head releasably on said stem, said type-key head having a shallow imperforate chamber therein overlying said metal plate, said plate serving to reinforce an adjacent wall of said chamber against flexure by impact on the type-key head.

5. A key-lever stem for typewriters and the like, adapted for detachably mounting a key-head thereon, the key-head having prong-receiving members, said stem being formed of a single piece of metal and including an offset portion folded on itself, a part of the fold adjacent the end of said offset portion being omitted to present a pair of co-extensive yieldable prongs for releasably engaging the key-head.

6. A key-lever stem for typewriters and the like, adapted for detachably mounting a key-head thereon, the key-head having prong-receiving members, said stem being formed of a single piece of resilient metal and including an offset portion folded upon itself, a part of the fold adjacent the ends of said offset portion being omitted to present a pair of co-extensive yieldable prongs, the ends of said prongs being oppositely directed for a positive engagement in the prong-receiving members of said key-head.

7. A metal type-key stem having two spaced resilient members with end portions oppositely turned outwardly, and a type-key head having a metal plate secured thereto, said plate having opposed marginal portions inturned to closely fit the end portions of said resilient members to securely hold said type-key head releasably on said stem.

8. A type-key stem adapted to form part of a key lever, for detachably mounting a key-head thereon, in combination with a key-head of solidified plastic material having prong-receiving means comprising an embedded metal piece with opposed downwardly extending side flanges and opposed downwardly and inwardly extending side flanges; said stem being formed of a single piece of spring metal of channel formation for a part of its length and presenting a pair of upwardly extending spaced side members, the ends of which provide oppositely directed prongs for engagement at their tips with said inwardly extending flanges, and for engagement at their side edges with said downwardly extending flanges.

WILLIAM F. HELMOND.
